UNITED STATES PATENT OFFICE.

GEORG WOLF, OF BERLIN, GERMANY, ASSIGNOR TO THE FIRM: BING-WERKE, VORMALS
GEBRÜDER BING AKTIENGESELLSCHAFT, OF NUREMBERG, GERMANY.

CALCULATING MACHINE.

Application filed July 8, 1922. Serial No. 573,549.

To all whom it may concern:

Be it known that I, GEORG WOLF, a citizen of Germany, residing at Berlin, Germany, have invented certain new and useful Improvements in Calculating Machines, of which the following is a specification.

My invention has reference to means for effecting the displacement of the counting gear carriage in calculating machines and the like in two opposite directions by means of keys, and for one or any number of digits. In the previous devices of this kind the carriage is displaced for one or several digits by the depression of one or the two shifting keys or side keys, and it has also been suggested already to arrange a center key for the purpose of shifting the carriage through any number of digits.

In view of these previous displacing and adjusting devices the present invention is particularly distinguished by the fact that the key levers to be depressed are not provided with pawls or dogs or are otherwise capable of individual movement of their own, but they are made in one piece so as to practically exclude failure of operation in the usual course of working, it being one of the objects of my invention to employ the least amount possible of springs or of spring acting pawls, dogs or the like.

The invention will be more fully described with reference to the accompanying drawing showing an embodiment thereof by way of example.

Figure 1 is a sectional view on the line C—D of Figure 3, the key levers being shown in the inoperative position.

Figure 2 is the same sectional view as Figure 1, but with the right hand locking key depressed so as to disengage the carriage locking means.

Figure 3 is a section on the line A—B of Figure 4, and

Figure 4 is a plan view of the carriage feeding means of the calculating machine.

Figures 5 to 7 illustrate details of the device.

The locking of the counting gear carriage *a* is effected in this device by means of a rigid lever *c* (Figure 7) pivotally mounted on a stud *b* in the frame of the machine at the outer end of which a roller *d* is provided which is adapted to be retained by a tension spring *e* in the notches *d'* of a rack bar *f*

secured to the counting gear carriage (Figure 1). If it is desired to displace the counting gear carriage (Figure 2), it becomes necessary to disengage the roller *d* from the notches *d'*, which is effected by means of the rigid unlocking lever *g* which is adapted to be operated alternately by the side keys *L* and *R*, and the central key *l*. The unlocking lever *g* is pivoted on the stud *h*, and is provided at its end opposite the carriage with a ball shaped portion *i* adapted to slide along the inclined surface *k* of the lever *c* (Figures 3 and 7). The inclined face *k* is so arranged that upon the depression of one of the side keys *L* or *R* the locking roller *d* is first disengaged without coming in contact with the rack teeth *d'*, and without interfering with the displacement of the carriage whereupon, as soon as the displacement of the carriage has been almost terminated, the roller drops back into the indentation and assists the displacement of the carriage.

The displacement of the carriage through several digits is effected by the depression of the central key *l* which presses against the bar *m* of the disengaging lever *g* (Figure 6). By means of the ball *i'* the lever *g* raises the locking lever *c*, which causes the roller *d* to be disengaged, so that the carriage *a* may be easily displaced at will into any digit place desired.

In order to displace the counting gear carriage *a* only for one digit means are provided as follows:

To the frame of the machine a supporting bracket is secured in which the cog wheel or pin carrying wheel *o* is rotatably mounted which is provided at its outer and inner sides with 6 pins *p* and *p'* respectively rigidly connected thereto on either side. Below the pins *p* the key levers *n* and *n'* (Figure 3) are mounted which are rotatable on the shaft *q*. If one of the side keys, for instance, *R*, is depressed, the unlocking lever *g* is rotated by means of the bar *m* by which means the roller *d* becomes disengaged from the notches *d'*. Upon the further depression of the said key lever *n'*, as shown in Figure 2, acts upon the pin *p* in the direction of the arrow, by which means the pin wheel *o* is rotated, until the succeeding pin *p* comes to abut against the side of the lever *n'*, thereby exactly limiting the stroke thereof. The pins *p'* on the

inner side of the pin wheel σ during this 5 partial rotation become engaged with the grooves r of the rack bar f , thereby displacing the carriage for one digit in the direction of the arrow (Figure 2). Upon releasing the key R the tensional spring s restores the key to its position of rest. At the same time the tensional spring e forces the roller d into the next succeeding notch 10 d' (Figure 2) of the rack bar f , and the pin wheel σ is locked in its position of rest by the cam faced portion of the lever c (Figures 1 and 7), while the succeeding pin p is moved into the operative position above 15 the key lever n' .

My invention is evidently not restricted to the particular configuration and arrangement of parts as herein shown and described, but changes and alterations may occur 20 without deviating from the spirit of my invention as set forth in the claims hereunto annexed.

I claim:—

1. Calculating machine comprising in 25 combination, a machine bed, a carriage mounted on said bed for lateral displacement, a ratchet wheel mounted on said bed and gearing with said carriage and a rigid rockable key lever directly engageable with 30 said wheel, said key being arranged for acting on one tooth of said ratchet wheel for rotating said wheel and for acting on the next succeeding tooth for locking said wheel.

35 2. Calculating machine comprising in combination, a machine bed, a carriage mounted on said bed for lateral displacement, a ratchet wheel mounted on said bed and gearing with said carriage, pins equidistantly mounted on said wheel and a rigid rockable key lever adapted to cooperate with said wheel in displacing said carriage, two faces being formed on said lever at an angle to one another, one face adapted to raise one pin so as to turn said wheel and another face adapted to form an abutment for the next succeeding pin so as to stop 45 said wheel.

50 3. Calculating machine comprising in combination, a machine bed, a carriage mounted on said bed for lateral displacement, a ratchet wheel mounted on said bed and gearing with said carriage, pins equidistantly mounted on either side of said 55 wheel and a rigid rockable key lever adapted to cooperate with said wheel in displacing said carriage, two faces being formed on said lever at an angle to one another, one face adapted to raise a pin on one side of said wheel so as to turn said wheel and another face adapted to form an abutment for the next succeeding pin so as to stop 60 said wheel, the pins on the other side of said wheel being in operative engagement with said carriage.

4. Calculating machine comprising in combination, a machine bed, a carriage mounted on said bed for lateral displacement, a ratchet wheel mounted on said bed and gearing with said carriage, pins equidistantly mounted on either side of said wheel and a rigid rockable key lever adapted to cooperate with said wheel in displacing said carriage, two faces being formed on said lever at an angle to one another one face adapted to raise a pin on one side of said wheel, so as to turn said wheel and another face adapted to form an abutment for the next succeeding pin so as to stop said wheel and a rack on said carriage adapted to be engaged by the pins on the other side of said wheel.

5. Calculating machine comprising in combination, a machine bed, a carriage mounted on said bed for lateral displacement, a ratchet wheel mounted on said bed and gearing with said carriage, pins equidistantly mounted on either side of said wheel and a rigid rockable key lever adapted to cooperate with said wheel in displacing said carriage, two faces being formed on said lever at an angle to one another, one face adapted to raise a pin on one side of said wheel so as to turn said wheel and another face adapted to form an abutment for the next succeeding pin so as to stop said wheel, a double rack on said carriage having one row of teeth adapted to be engaged by the pins on the other side of said wheel and locking means engageable with the other row of teeth of said rack.

6. Calculating machine comprising in combination, a machine bed, a carriage mounted on said bed for lateral displacement, a ratchet wheel mounted on said bed and gearing with said carriage, pins equidistantly mounted on either side of said wheel and a rigid rockable key lever adapted to cooperate with said wheel in displacing said carriage, two faces being formed on said lever at an angle to one another, one face adapted to raise a pin on one side of said wheel so as to turn said wheel and another face adapted to form an abutment for the next succeeding pin so as to stop said wheel, a double rack on said carriage having one row of teeth adapted to be engaged by the pins on the other side of said wheel, locking means engageable with the other row of teeth of said rack and a releasing lever adapted to act on said locking means so as to unlock said carriage.

7. Calculating machine comprising in combination, a machine bed, a carriage mounted on said bed for lateral displacement, a ratchet wheel mounted on said bed and gearing with said carriage, pins equidistantly mounted on either side of said wheel and a rigid rockable key lever adapted to cooperate with said wheel in displac-

ing said carriage, two faces being formed on said lever at an angle to one another, one face adapted to raise a pin on one side of said wheel so as to turn said wheel and another face adapted to form an abutment for the next succeeding pin so as to stop said wheel, a double rack on said carriage having one row of teeth adapted to be engaged by the pins on the other side of said wheel,

a locking lever engageable with one row of 10 teeth on said rack, a cam face on said locking lever and a releasing lever adapted to act on said cam face so as to rock said locking lever out of engagement with said rack and to thereby release said carriage. 15

In testimony whereof I affix my signature.

GEORG WOLF.
